J. PRECIOUS

ELECTRICAL TAP SOCKET

Filed Dec. 15, 1923

Patented June 29, 1926.

UNITED STATES PATENT OFFICE.

JOSEPH PRECIOUS, OF PROVIDENCE, RHODE ISLAND.

ELECTRICAL TAP SOCKET.

Application filed December 15, 1923. Serial No. 680,904.

This invention relates to electrical tap sockets and more particularly to a socket embodying a cap or plug and switch which may serve the usual function of the ordinary key switch, and providing a practical means for tapping the current from the socket for supplemental uses.

The invention consists of a suitable insulated body provided with the usual socket 10 for a lamp bulb and four contact members whereby the current may be taken from the body for supplemental purposes on one side of the plug and the opposite side of the body having contacts engaged by a cap 15 or plug connection which is associated with suitable switch mechanism for controlling the lamp circuit.

An object of this invention is to construct a tap socket so that the light circuit will not interfere with the use of the supplemental connection or the supplemental connection interfere with the light circuit and to provide means whereby the light circuit is always under the control of the tap socket 25 and its associated switch.

The invention consists of certain novel features of construction and combination of parts which will be hereinafter described and pointed out in the claim.

80 In the accompanying drawings:

Figure 1 is a view in elevation of the tap socket with its various connections;

Figure 2 is a plan view in elevation showing the inner faces of the two sections of the 35 tap socket;

Figure 3, is a vertical sectional view on the line 3—3, of Figure 1;

Figure 4, is a top plan view of the tap socket with the insulated plug removed;

40 Figure 5, is a bottom plan view of the socket for the lamp bulb;

Figure 6 is a view in elevation of one of the contact terminals;

Figure 7 is a plan view of the blank for 45 forming the terminal; and

Figure 8, is a diagrammatical view of the circuits.

The tap socket is constructed of any suitable insulating material and is composed of 50 two sections 10 and 11. Connected to the section 10 is the usual threaded sleeve contact 12 and to the section 11 is the threaded sleeve contact 13. Received within the threaded sleeve contact 12 is an insulated 55 plug 14 through which extends a binding screw 15 which engages a conductor 16

located in the recessed portion of the section 11 and the spring contact 17 is mounted upon the stem 15 and engaged by the end of the lamp bulb when screwed into the 60 threaded sleeve 13. Binding screw 15 and conductor 16 form the means for holding the two sections 10 and 11 and the insulated plug 14 together.

The inner faces of the two sections 10 and 65 11 are provided with four recessed compartments 18. In two diametrically opposed compartments 18 of the section 10 are mounted and received contacts D and C and in two diametrically opposed compartments 70 18 of the section 11 are contacts B and A. The contacts of these two sections are not arranged in the same compartments of their respective sections. The vacant compartments of the section 10 will receive the contacts A and B of section 11 when the two 75 adjoining faces of the sections are brought together, and the vacant compartments of section 11 will receive the contacts C and D of the section 10. These compartments are 80 formed so that the walls of the sections, as well as the partition or dividing walls will come in contact with each other so that there will be no danger of short circuiting between the various contacts. The contacts 85 C and D of section 10 are connected thereto and to the sleeve contact 12 by binding screws 19 and 20 so that the circuit is carried from the sleeve 12 to each of these contacts. These screws are illustrated in Figure 4.

The contacts A and B of section 11 are attached to section 11 by means of binding screws 21 and 22. The binding screw 21 having engagement with the threaded socket 13 and the binding screw 22 having 95 engagement with the conductor 16. The contacts B and D when the plug sections are assembled form the means whereby a circuit may be completed at any time, that is, these contacts are always "live" and therefore 100 ready for use at all times. These contacts are adapted to be engaged by spring terminals 23 carried by a line tap plug 24.

The contacts A and C are adapted to be 105 engaged by similar line tap plug 25 which is provided with the usual two spring terminals 26 for completing the circuit through the tap socket to the lamp 27. The tap plug 25 and its terminals are provided with a switch 28 which is connected thereto by a 110 suitable wiring 29 so that the switch may be carried to any convenient location in the

room and operated for causing the lamp to be lighted or extinguished. In this connection it might be stated that the circuit through contacts C and A is through the binding screw 15 to conductor 16 and spring contact 17 then through the lamp socket to sleeve 13, and then through screw 21 and contact A. Contact C is connected to the sleeve 12 by screw 19 thereby completing the circuit to these contacts when the tap plug 25 is inserted causing each of its terminals 26 to engage one of the contacts A and C. The lamp 27 is caused to be lighted when the button of the switch 28 is operated, and extinguished upon a similar operation of the switch. The circuit for the "live" side of the socket through terminals B and D is as follows: The contact D is connected to the sleeve 12 by binding screw 20, whereas the contact B receives its circuit through the binding post or screw 15, conductor 16 and screw 22, and upon the insertion of the contact terminals 23 of the tap plug 24 causing each of the terminals 23 to engage a contact D and B current will be carried through the wires 30 to any suitable source. From the foregoing it will be seen that the terminals B and D are always "live" and ready for use regardless of the position of the button 31 of the switch 28. The lamp circuit, however, is always under control of the button 31 of the switch 28 and the lamp may be lighted or extinguished at any time upon the operation of the button 31. However, when the tap plug 25 and its terminals 26 are removed from engagement with the contacts A and C, the current will not pass to the light and the same can not be used until the tap plug has been brought into engagement with the contacts A and C of the tap socket.

In Figures 6 and 7 is illustrated the contacts A, B, C and D. In Figure 7, the

blank 32 is illustrated and when folded or bent into shape will produce the structure 45 shown in Figures 6 and 2. Attached to the contact is a conductor plate 33 which is provided for engagement with the binding screws employed for attaching it to the sections of the tap socket. These contacts are 50 constructed for receiving terminals which may be arranged either in horizontal plane with respect to the plugs 24 and 25, or vertical. Only the horizontal terminals have been illustrated in Figure 1, and these terminals engage the contacts 34, 34, of Figure 6, but if the vertical terminals were employed, the terminal would engage a side of each of the contacts 34 and 35.

From the foregoing it will be seen that a 60 tap socket has been provided whereby current may be taken therefrom at any time without the operation of a switch and that a control has been provided for the lamp circuit which is dependent upon a tap plug 65 25 for causing the lamp circuit to function. It is necessary that the terminals 26 of the tap plug be brought into engagement with the contacts A and C and the button 31 of the switch 28 operated before the circuit 70 will be complete for lighting the lamp.

Having described my invention, what I claim is:

In a tap socket, the combination of plug and socket members secured together, each 75 of the adjacent faces of the two members provided with a number of compartments, stationary contact terminals located in compartments of each member and received in compartments of the adjacent member, a 80 contact terminal of each member forming together constantly live contacts for a branch circuit, and two contacts, one of each member, adapted for connection in establishing another circuit.

JOSEPH PRECIOUS.
